UNITED STATES PATENT OFFICE.

THADDEUS F. BAILY AND FRANK T. COPE, OF ALLIANCE, OHIO, ASSIGNEES TO THE ELECTRIC FURNACE COMPANY, OF ALLIANCE, OHIO, A CORPORATION OF OHIO.

MELTING-FURNACE.

1,272,186.

Specification of Letters Patent.

Patented July 9, 1918.

Application filed September 4, 1917. Serial No. 189,466.

To all whom it may concern:

Be it known that we, THADDEUS F. BAILY and FRANK T. COPE, citizens of the United States, both residing at Alliance, in the 5 county of Stark and State of Ohio, have invented a new and useful Melting-Furnace, of which the following is a specification.

Our invention relates to improvements in furnaces wherein a current of electricity 10 passed through resistance material is employed to produce the necessary heat, and has more especial reference to a melting furnace in which one or more resistance troughs are located above and surround the 15 hearth upon which the material to be melted is placed.

The object of the present invention is to generally improve electric furnaces of this 20 type by more properly concentrating the heat therein upon the material to be melted.

Another object is to so dispose the walls of the furnace that the greater part of the heat 25 therein will be either radiated direct, or reflected upon the hearth containing the material to be melted.

A further object is the provision of a furnace of the character referred to in which one or more resistance troughs are located above and surround or partially surround 30 the hearth.

A still further object is the provision of a furnace of this type in which a concave or 35 conical roof is provided in combination with a concave hearth and one or more resistance troughs are located between the roof and 40 hearth, a central opening being provided through which heat rays may be reflected from the roof to the hearth.

A still further object is the provision of such a furnace in which a circular resistance 45 trough is located above the hearth.

With these objects in view the invention 50 consists in the novel construction and arrangement of parts, hereinafter described, 45 illustrated in the accompanying drawings, and particularly pointed out in the appended claims, it being understood that various changes in the form, proportions, size and minor details of construction may be 55 made within the scope of the appended claims, without departing from the spirit or sacrificing any of the advantages of the invention.

In the drawings:

55 Figure 1 is a vertical sectional view

through a circular furnace constructed in accordance with our invention.

Fig. 2 is a section on the line 2—2, Fig. 1.

Fig. 3 is a section on the line 3—3, of Fig. 1.

Fig. 4 is a section in the line 4—4, Fig. 1.

Fig. 5 is a section on the line 5—5, Fig. 1.

Fig. 6 is a view partly in elevation and partly in longitudinal section of a rectangular furnace constructed in accordance with 65 our invention.

Fig. 7 is a section on the line 7—7, Fig. 6.

Fig. 8 is a section on the line 8—8, Fig. 7.

Fig. 9 is a sectional view showing the terminal construction of one of the electrodes such as are used in each form of the 70 furnace.

Similar numerals of reference indicate corresponding parts throughout the several figures of the drawings.

Referring more especially to the construction illustrated in Fig. 1 to Fig. 5 inclusive, of the drawings, the numeral 1 indicates a metal plate upon which the base 2 of the furnace is supported, this base being composed of suitable insulating material such as bricks formed of kieselguhr, a metal plate 3 being preferably located upon said brick base and supporting the brickwork 4 preferably formed of fire brick and provided 80 with the concave hearth 5 which is lined with suitable heat resisting material and provided at one side with a reduced neck 6 having a pouring spout 7. A circular wall 8, formed of fire brick or other suitable material is supported upon the brickwork 4 and a roof 9 preferably concave as shown, is provided over said circular wall, thus forming a heating chamber between the 85 hearth, roof and circular wall.

Mounted within the heating chamber intermediate the hearth and roof thereof and spaced from the circular side wall, is a resistance trough 10, preferably circular as shown. This trough is filled with a resistance body, consisting of a carbonaceous material in granular form, such as crushed coke, graphite, carbon or the like, said resistance body being designated by the numeral 11. The trough is preferably formed 100 of refractory material or the like and comprises the bottom wall 12 and the circular upright walls 13, and is supported upon the radial supporting walls 14, composed of fire brick or other suitable heat resisting ma- 110

material. Embedded in the resistance material, preferably at diametrically opposite sides of the trough are the electrodes 14^a, said electrodes extending through the furnace walls as best shown in Figs. 2 and 6. It will be understood that the electrodes 14^a should be arranged in an electric circuit such construction being well known in this art, electric wires being connected to the terminals 15 of the electrodes and leading to a suitable source of electricity. When the current is supplied to the electrodes it will be conducted from one electrode to the other through the resistance material, thus raising the resistance material to an intense heat.

A metal casing 16 is preferably provided around the furnace and it will of course be understood that furnaces of this type can be mounted so that they may be tilted to pour the melted metal therefrom and for this purpose trunnions 17 are provided upon diametrically opposite sides of the metal casing and may be journaled in any suitable bearings in order that the furnace may be rocked or tilted upon said bearings when it is desired to pour the melted metal from the spout 7.

The heat rays which radiate downwardly from the resistance trough will strike directly upon the hearth containing the metal to be melted, while those rays which radiate upwardly from the trough will strike the arched roof and although a portion of the heat will be absorbed by the roof the greater majority will be reflected through the central opening in the trough upon the material upon the hearth. By this construction the greater majority of the heat which radiates from the resistance material in the form of heat rays will either strike directly or be reflected back upon the hearth, thereby maintaining the working hearth at a high temperature. It will, of course, be understood that it is not necessary to form the roof in the shape of an arch, as a roof formed of angular walls arranged with proper relation to the resistance trough the hearth will produce equally favorable results.

In Figs. 6 to 8 inclusive is illustrated a modified form of the invention, showing a rectangular furnace. Although only two resistance troughs are shown in this form of the furnace it will be understood that resistance troughs may be provided around the four walls of the heating chamber or a continuous resistance trough may be provided around the interior of the heating chamber without departing from the invention. This form of furnace is preferably fixedly mounted upon the I-beams 18 and is provided with the metal plate 19 which rests upon said I-beams and carries the base portion 20 formed of heat insulating brick or the like, a metal tank 21 being

located above said fire brick base and carrying the hearth 22 provided with a suitable lining 23, said hearth being channel shaped as shown in the drawings, the bottom thereof being inclined toward the neck 24 which is provided with a pouring spout 25 arranged to be closed with a plug in the usual manner. The resistance troughs 26 are spaced from the side walls of the furnace and mounted upon the spaced supporting walls 27. Each of these troughs is filled with a carbonaceous material in granular form such as used in the trough 10 and electrodes 28 are provided at opposite ends of each trough and connected to an electric circuit. An arched roof 29 is provided upon the heating chamber of the furnace and a metal casing 30 covers the entire furnace and is supported by means of the structural iron frame 31. Door openings 32 are provided in opposite ends of the furnace and are arranged to be closed by means of the doors 33 which are carried upon cables 34 and operated by means of fluid cylinders 35. This latter construction, however, is covered in former patents granted to the applicants and no claim is made to the specific construction thereof.

When it is desired to charge the furnace the cylinders 35 are operated to open the doors after which the metal may be placed in the hearth and the doors closed. When the metal has been melted the plug 36 is removed from the spout 25 allowing the metal to run through the neck 24 and spout 25. Rabbling holes 37 are provided in the side walls of the furnace.

In this form of the furnace as well as the other form it will be seen that there is a complete circulation around the resistance troughs and that the greater part of the heat generated from the resistance troughs is either radiated directly upon the hearth containing the metal to be melted or is reflected by means of the arched roof between the troughs and upon the hearth. With this construction it has been found that a high temperature can be maintained upon the hearth as the heat radiating downwardly from the resistance trough is supplemented by the heat reflected by the roof the heat rays from the two sources tending to bring the bottom of the heating chamber to a high temperature. The heat radiated from the sides of the trough in the present construction is of course not wasted as it maintains the center of the heating chamber at a high temperature.

The form of furnace illustrated in Figs. 1 to 5 is provided with a removable roof 38 having a metal casing 39 which extends down into the channel 40 which channel contains sand or other heat insulating material for forming a seal at the joint of the roof of the furnace. This roof is preferably ar-

ranged approximately in the same horizontal plane as the resistance trough in order that it may be raised to allow access to the resistance trough when it is desired to recharge the same. For the purpose of easily raising or lowering the roof when desired, spaced radially disposed internal screw threaded lugs 41 are provided upon the metal casing of the roof, which lugs are located directly above the lugs 42 carried by the casing of the furnace, shafts 43 being located through said lugs and provided upon their upper extremities with screw threaded portions 44 engaging the internal screw threads of the lugs 41. Sprocket wheels 45 are provided upon the lower extremities of these shafts, all of the sprocket wheels being connected by means of a chain 46 and one of the shafts is provided with a beveled gear 47 which meshes with a beveled gear 48 mounted upon the shaft 49, the hand wheel 50 being provided for rotating said shaft, thereby rotating all of the shafts 43 in unison and raising and lowering the roof a sufficient distance to allow access to the resistance trough.

We claim:

1. In an electric furnace of the resistance type the combination of a heating chamber, a hearth located in the bottom of said heating chamber, a resistance trough located above said hearth and extending around the walls of the heating chamber and a roof so arranged above said resistance trough that heat rays radiating upwardly from said trough will be reflected upon said hearth while heat rays radiated downwardly from said resistance trough will strike directly upon said hearth.
2. In an electric furnace of the resistance type, the combination of a heating chamber, a hearth located at the bottom of said heating chamber, a continuous resistance trough located above said hearth and provided with a central opening and a roof so arranged above said resistance trough that heat rays radiating upwardly from said resistance trough will be reflected through said central opening upon said hearth while heat rays radiating downwardly from said resistance trough will strike directly upon said hearth.
3. In an electric furnace of the resistance type, the combination of a heating chamber, a hearth located in the bottom of said heating chamber, a circular resistance element located above said hearth and a roof so arranged above said resistance element that heat rays radiating upwardly from said resistance element will be reflected upon said hearth while heat rays radiating downwardly from said resistance element will strike directly upon said hearth.

4. In an electric furnace of the resistance type, the combination of a circular heating chamber, a concaved hearth located in the bottom of said heating chamber, a circular resistance element located above and spaced from said hearth and a roof so arranged above said resistance element that heat rays radiating upwardly from said resistance element will be reflected through the center thereof upon said hearth while heat rays radiating downwardly from said resistance element will strike directly upon said hearth.

5. In an electric furnace of the resistance type, the combination of a circular heating chamber, a concaved hearth located in the bottom of said heating chamber, a circular resistance element located above and spaced from said hearth and provided with an open center, a roof so arranged above said resistance element that heat rays radiating upwardly from said resistance element will be reflected through the central opening thereof upon said hearth while heat rays radiating downwardly from said resistance element will strike directly upon said hearth, a spout connected with said hearth and means for tilting the furnace to pour the melted metal from said spout.

6. In an electric furnace of the resistance type, the combination of a heating chamber, a hearth located in the bottom of said heating chamber, radial walls provided within said heating chamber above said hearth, a continuous resistance element supported upon said radial walls and spaced from the inner walls of the heating chamber and a roof so arranged above said resistance element that heat rays radiating upwardly from said resistance element will be reflected through the center thereof upon said hearth, while rays radiating downwardly from said resistance element will strike directly upon said hearth.

7. In an electric furnace of the resistance type, the combination of a heating chamber, a hearth located in the bottom of said heating chamber, spaced walls provided within said heating chamber around the inner walls thereof and extended above said hearth, a resistance element supported upon said spaced walls and spaced from the inner walls of the heating chamber and a roof so arranged above said resistance element that heat rays radiating upwardly from said resistance element will be reflected upon said hearth, while heat rays radiating downwardly from said element will strike directly upon said hearth.

In testimony that we claim the above, we have hereunto subscribed our names.

THADDEUS F. BAILY.
FRANK T. COPE.
